(57) **CLAIM**

(**) Term: **14 Years**

The ornamental design for a visual pattern (combination of flowers and leafs) to be used on an absorbent article, as shown and described.

(21) Appl. No.: **29/235,916**

(22) Filed: **Aug. 8, 2005**

DESCRIPTION

(51) **LOC (8) Cl.** 24-04

FIG. 1 is a perspective view of the absorbent article, namely a pantiliner, provided with the visual pattern (combination of flowers and leafs);

(52) **U.S. Cl.** **D24/124**

FIG. 2 is a perspective view of an alternative embodiment of the absorbent article of FIG. 1;

(58) **Field of Classification Search** D24/124-126;

FIG. 3 is a perspective view of another alternative embodiment of the absorbent article of FIG. 1;

D5/35, 37, 53, 58; D6/576

FIG. 4 is a top-side elevation view of the absorbent article of FIG. 3;

See application file for complete search history.

FIG. 5 is an elevation front view thereof;

(56) **References Cited**

FIG. 6 is an elevation back view thereof;
